UNITED STATES PATENT OFFICE.

JEREMIAH CLOSE AND IRA BUCKMAN, JR., OF BROOKLYN, NEW YORK.

IMPROVEMENT IN HINGES.

Specification forming part of Letters Patent No. 51,426, dated December 12, 1865.

To all whom it may concern:

Be it known that we, JEREMIAH CLOSE and IRA BUCKMAN, Jr., of the city of Brooklyn, in the county of Kings, State of New York, have invented a certain new and useful improvement in right and left opening double-acting spring butt-hinges for doors for public and other buildings; and the following is a full, clear, and exact description of the same, reference being had to the accompanying drawings, making a part of this specification, in which—

Figure 1 represents a cross-section of a closed right and left opening spring butt-hinge. Fig. 2 shows a view of the same with left wing open at right angle. Fig. 3 is another view with the right leaf open, the other closed. Fig. 4 shows a front face view with both leaves or wings spread open. Fig. 5 is a vertical section through the spread butt-hinge.

The object of our invention is to make double-jointed hinges in which the springs are incased in the joint or around the pintle to allow the door to be opened either inward or outward, thus making one pair of hinges answer the better purpose of two pairs of butts, dispensing entirely with the tumbling stiles, which are very objectionable in more ways than one, as may be fully demonstrated.

Our invention consists in constructing butt-hinges with three leaves in such manner as to allow the door to swing on them and open either inward or out, the center leaf forming a portion of the two joints, one on each side of the door, in which coiled springs may be placed of sufficient power to close the door, the operation of the spring upon the joint of the hinge being similar to those embraced in the Patents Nos. 29,212 and 36,976.

To enable others skilled in the art to make and use our improved right and left opening spring butt-hinge, we will describe it more fully, referring to the drawings, and to the letters of reference marked thereon.

For all heavy doors in public buildings and places of much resort it is desirable, and has become almost indispensable, to have the doors swing both ways, either in or out, and, when passed, to close themselves and remain

in their proper place, which must necessarily be done by counteracting forces, there being no rabbet or obstruction in the jambs or door-casings to fix or hold them in position. For this purpose we construct our simplified improved spring butt-hinge, which consists of two outside leaves or wings, A and A², the one to be screwed to the jamb or casing, the other to the edge of the door.

Between the leaves A A² is the connecting-plate B, which has the knuckles C C, for the joints of the hinges on both of its edges, into which similar knuckles formed on the leaves A A² are fitted, so that one leaf folds up against one side of the plate B and the other on the opposite side when the door or hinge is closed, as seen in Fig. 1.

Helical or coiled springs f f may be placed in sleeves or openings d d within the joints of the hinges, they being of sufficient power and so arranged in relation to the plate B that they tend to hold the leaves A A² closed up against the sides of the plate when not forced away from it, as in opening the door in either direction, as seen in Figs. 2 and 3.

Thus it will be seen that in hinging doors by butts constructed upon our improved plan as above described but a single pair of butts or hinges are necessary, whereas in hanging doors with the two-leaved butts, as those set forth in the Patents Nos. 29,212 and 36,976, above referred to, it requires two pairs of the hinges, and between the pair that allows the door to open one way and those that admit of its being opened in the other direction there has to be placed a "tumbling stile," as it is technically called, so that when swung in one direction the strip or tumbling stile opens with the door, and when opened in the other direction it remains held against the jamb or door-casing and varies the width of the opening very essentially.

Thus it will be seen that our improved double-acting double-jointed butt-hinge will entirely remedy all of the difficulties heretofore existing and meet all of the requirements, and furnish a cheaper, more substantial, and much neater mode of hinging doors which operate uniformly well both ways.

We do not claim anything in relation to the spring or its location or manner of operating to close the door; but,

Having fully described our invention, what we claim as new, and desire to secure by Letters Patent, is—

The center plate, B, having a hinge-joint on both edges, in combination with the sleeves *d*

d, the springs *ff*, and outside leaves, A A², substantially as and for the purposes herein specified.

JEREMIAH CLOSE.
IRA BUCKMAN, JR.
